UNITED STATES PATENT OFFICE.

JAMES G. HENDERSON, OF CINCINNATI, OHIO.

DESIGN FOR A MEMORIAL CARD.

SPECIFICATION forming part of Design No. 22,477, dated May 30, 1893.

Application filed April 21, 1893. Serial No. 471,343. Term of patent 3½ years.

To all whom it may concern:

Be it known that I, JAMES G. HENDERSON, a citizen of the United States, residing at Cincinnati, in the county of Hamilton and State of Ohio, have invented a new and useful Improvement in Designs for Memorial Cards, which improvement is fully set forth in the following specification and accompanying illustration.

- 10 My invention consists of a memorial card, the several features of which are so combined as to form an appropriate symbol, especially adapted to perpetuate the remembrance of deceased relatives or friends.
- 15 The main surface of the card presents to view a grave-yard scene with the usual accessories, and a funeral procession in the act of departing therefrom. The central and principal feature of the design is the form of a
- 20 released spirit clad in a flowing robe and as-

cending to the regions above where angels are seen in waiting to welcome and conduct it to its home in paradise.

In the foreground of the card is a tombstone, having a blank tablet. The ornamental borders of the card are further embellished by suitable symbols, consisting of an anchor at the top, a dove and sprig at the bottom, a book and ark on the left and an hour-glass and scythe on the right.

30

What I claim as new is—

A design for a memorial card substantially as shown and described.

In testimony that I claim the foregoing I have hereunto set my hand this 28th day of 35 March, 1893, in the presence of witnesses.

JAMES G. HENDERSON.
